KEYING CONTROL SYSTEM FOR
OSCILLATORS

Herbert F. Storm and Ernest W. Hutton, Schenectady, N. Y., assignors to General Electric Company, a corporation of New York

Application November 20, 1946, Serial No. 711,164

2 Claims. (Cl. 250—36)

1

This invention relates to control systems, and more particularly to systems for controlling keying operations of high power electric valve type oscillators, and it has for an object the provision of a simple, reliable and improved control system of this character.

Another object of the invention is the provision of a keying control system which effects substantial economies in the electrical power consumed in the keying operation. Still another object is to provide increased reliability and to effect economies in maintenance by minimizing the burning out of parts. In electric valve oscillators, the grid bias voltage is usually obtained from the voltage across a resistor in the grid circuit in which direct current is obtained by grid rectification. This grid bias resistor may be a lamp bank comprising a number of incandescent lamps connected in series. In high power oscillators, a number in excess of 20 such lamps frequently is required for the grid bias resistor.

Accordingly a more specific object of the invention is the provision of a relatively low power control system for supplying to the bias resistor a negative variable voltage which is just sufficient to terminate the oscillations and to maintain the oscillator turned off for a period which varies from a fraction of a second to several minutes or longer periods of time.

In carrying the invention into effect in one form thereof, a relatively high power electric valve type oscillator is provided with a grid bias resistor in which a direct current is obtained by means of grid rectification. The grid bias voltage is obtained from the voltage drop across this resistor. For the purpose of controlling or keying the oscillator, i. e. turning the high frequency power on or off at will for periods varying from a fraction of a second to a few minutes, means are provided for supplying to the bias resistor a negative pulse voltage of sufficient magnitude to terminate the oscillations. This pulse voltage is decreased in magnitude at a rate substantially equal to the rate of decay of the high frequency oscillations. At the termination of the oscillations a hold-off voltage is supplied to the bias resistor of which the magnitude is substantially less than the value required to terminate the oscillations but is sufficient to maintain the oscillator inactive once the oscillations have been terminated.

For a better and more complete understanding of the invention, reference should now be had to the following specification and to the accompanying drawings of which Fig. 1 is a simple, schematic diagram of an embodiment of the in-

2

vention, and Figs. 2, 3, 4 and 5 are characteristic curves which facilitate an understanding of its operation.

Referring now to the drawing, an oscillator 1 is supplied from a suitable source of voltage which is represented by the terminal 2 and the ground connection 3. Although this oscillator may be of any suitable type, it is illustrated as a conventional class C Colpitts oscillator.

The tank circuit of the oscillator comprises the inductance 4 and the capacitors 5 and 6. The coupling between the tank circuit and the anode and grid circuits comprise the capacitors 7 and 8.

A negative bias voltage for the grid 9a of the oscillator valve 9 is obtained from the voltage drop across a grid bias resistor 10 in which a direct current is obtained by means of grid rectification. The grid biasing resistor is preferably a lamp bank containing a plurality of incandescent lamps 10a, 10b, 10c, 10d, etc. Although the grid bias resistor is illustrated as comprising only four lamps, it is understood that in practice a much larger number of lamps is employed. For example, in a typical high powered oscillator the grid bias resistor comprises 23 such lamps.

During normal operation, i. e. during the oscillating period, current flows through the bias resistor in such direction that a negative bias voltage with respect to ground is produced at the terminal 11. This condition is represented in Fig. 2 in which ordinates represent voltage and abscissae represent time. Ground voltage is represented by the horizontal line 0—0 and the negative grid bias voltage is represented by the horizontal line 12.

During the period of oscillation a portion of the tank circuit high frequency voltage is supplied to the grid circuit through the coupling capacitors 7 and 8. The total grid voltage is thus the sum of the bias voltage E_b and the high frequency voltage which is obtained from the tank circuit is represented in Fig. 1 by the sinusoidal curve 13.

During the portion of the cycle in which the grid voltage is positive, current flows in the anode circuit of the oscillator valve 9. This current is necessary to sustain the oscillations.

For the purpose of stopping the oscillation, means are provided for supplying a negative pulse voltage to the grid circuit to increase the original negative bias. The oscillations can be stopped by increasing the negative bias voltage by an amount equal to the crest value of the grid voltage $E_{g\ max}$ of the grid voltage E_g . For reliable operation, the bias voltage should be made more negative by an additional marginal amount E_m . Thus, the

total voltage E_s which is required to stop oscillation is the sum of the operating grid bias voltage E_c , the crest value of the grid voltage E_g max. and the safety marginal amount E_m , as illustrated in Fig. 3.

If this stopping voltage is maintained for the period in which no oscillations are wanted, two particular difficulties arise: 1, the grid bias resistor which is illustrated as comprising a plurality of lamps cannot be overloaded on a continuous basis without burning out the lamps; 2, in energizing the grid bias resistor from an external source having a voltage E_s , a large amount of power is consumed. The prevention of oscillations can be accomplished by a much smaller bias voltage than that which is required to initiate the termination of the oscillations. Consequently, maintaining the negative bias voltage throughout the stopping period at the value E_s would result in a very considerable waste of power.

In order not to waste power, a negative pulse voltage is supplied to the grid circuit which is of sufficient magnitude to initiate the termination of the oscillations. This pulse voltage is followed by the application of a moderate bias voltage which at any instant is just large enough to prevent a resumption of oscillations.

In Fig. 4 the grid voltage E_g of the oscillator is first shown during a normal oscillating condition. It is represented by the sinusoidal portion 14 of the curve. At the time T_0 the stopping pulse E_s is applied between the terminal 11 and ground. This pulse forces the grid voltage negative to such an extent that the grid voltage remains negative and the flow of anode current in the oscillator valve is prevented. As a result the oscillations in the tank circuit 4, 5, 6 will decay and the high frequency voltage which is supplied from the tank circuit to the grid circuit will also decay as represented in Fig. 4 by the sinusoidal curve 14a of diminishing amplitude. In a conventional oscillator a much greater number of cycles than illustrated in Fig. 4 will be required before the residual oscillations may be considered to be negligible. It may be assumed that this condition is attained at the time T_1 . Then the stopping pulse E_s may be terminated and a moderate holding bias E_{ch} will suffice to prevent oscillations from starting.

If a rectangular-shaped stopping pulse voltage, such as illustrated in Fig. 4, is applied, the marginal safety voltages E_{m1} , E_{m2} , E_{m3} for the successive cycles become larger than necessary, since the high frequency voltage supplied from the tank circuit to the grid circuit begins to decay at the instant of application of the stopping pulse.

The marginal safety values of voltage are prevented from exceeding the necessary value for successive cycles by applying a pulse voltage of declining amplitude, with the result that the component parts for generating such pulse become smaller and less expensive because the pulse or declining amplitude takes less energy than the rectangular pulse. Furthermore, the energy dissipated in the lamp bank grid bias resistor is reduced to a value that will not burn out the lamps.

For the purpose of supplying to the grid circuit a negative voltage of diminishing magnitude, a circuit which includes the rectifier valve 15 and a capacitor 16 is provided. This rectifier valve is supplied from a suitable source of alternating voltage which is represented by the supply lines 17 to which the valve is connected

through the primary winding 18a and secondary winding 18b of a transformer 18. The rectifier valve 15 and the transformer 18 constitute a "trickle charger" which charges the capacitor 16 through a resistor 19 to the voltage E_s which is required to initiate the termination of oscillations. One terminal of the capacitor 16 is connected by means of the conductor 20 to the terminal 11 in the grid circuit of the oscillator valve. A thyratron valve 21 is connected between the other terminal of the capacitor 16 and ground. The high voltage to which the capacitor 16 is charged is impressed across the grid bias resistor 10 by the firing of the thyratron valve 21.

A direct voltage for controlling the thyratron 21 is obtained from the source 17 by means of a full wave rectifier valve 22 to which it is connected through the transformer 23. The rectified voltage is filtered by means of capacitors 24 and 25 and inductance 26 and is supplied to the terminals of a voltage divider comprising resistors 27, 28, 29 and 30. As shown, the cathode 21b of the thyratron is connected to the grounded common point of the resistors 29 and 30 of the voltage divider, and the grid 21c is connected to the point between the resistors 27 and 28 of which the voltage is negative with respect to the point to which the cathode is connected. Thus, the thyratron 21 is maintained at cut-off.

For the purpose of providing a hold-off voltage after the stopping pulse voltage has decayed to the hold-off value, a polyphase rectifier 31 is provided. This rectifier is illustrated as comprising a plurality of thyratron valves 32, 33 and 34 and a transformer 35 having a delta-connected primary winding 35a and a Y-connected secondary winding 35b.

The primary winding 35a of the transformer is supplied from a suitable source of polyphase voltage which is represented by the three supply lines 36 to which it is connected by means of an auto transformer 37. The positive output terminal 31a of the rectifier is connected to ground, and the negative terminal 31b is connected to the terminal 11 of the grid bias resistor.

The rectifier 31 is arranged for 3-phase operation in order to prevent the hold-off voltage from ever decreasing to zero. The polyphase rectifier having the least number of phases whose voltage never reaches zero without a filter is a 3-phase rectifier.

While the oscillator is oscillating this rectifier is ready to fire. The grids of the three valves 32, 33 and 34 are effectively grounded through the resistor 38. However, while the oscillator is oscillating the rectifier valves will not fire because the negative voltage from the grid bias resistor which is applied between the output terminals 31a and 31b of the rectifier exceeds the anode voltages supplied by the transformer secondary winding 35b. In other words, the anode voltage of the valves 32, 33 and 34 will be negative during oscillation.

For the purpose of initiating the termination of oscillations at will, a switching device 39 and an electromagnetic contactor 40 controlled thereby are provided. The switching device 39 is illustrated as a manually operated push button type switch having normally open contacts 39a.

With the foregoing understanding of the elements and their organization, the operation of the system will be readily understood from the following detailed description.

It is assumed that the oscillator is oscillating. Under this condition the high frequency grid

voltage is represented by the sinusoidal curve 41 in Fig. 5. Since the push button switch 39 is open and the contactor 40 is in the deenergized condition, the grid 21c of the thyratron 21 is connected to a point on the voltage divider 27, 28, 29 which is so negative with respect to the voltage of the cathode 21b that the thyratron is non-conducting. As a result, the capacitor 16 is charged to maximum voltage by means of voltage supplied from the transformer 18 and rectifier valve 15.

It is assumed that it is desired to terminate the oscillations of the oscillator at a time T_0 . This is accomplished by closing the contacts of the push button switch 39 thereby to complete an energizing circuit of the operating coil of the contactor 40. In response to energization, the contactor 40 closes its normally open contacts 40a and 40b and opens its normally closed contacts 40c and 40d. In closing, contacts 40a momentarily connect the grid 21c of thyratron 21 to ground through the capacitor 42. As a result, the thyratron 21 is rendered conducting and capacitor 16 is discharged through the thyratron thereby applying a negative pulse voltage between ground and the terminal 11 of the grid bias resistor 10. This negative pulse voltage is represented in Fig. 5 by the voltage E_s at time T_0 .

The discharge of the capacitor 16, which reduces the anode voltage of thyratron 21, together with the buildup of a negative voltage on the grid 21c, as a result of the charging of capacitor 42, will prevent continued firing of the thyratron and permit only one discharge of the capacitor 16 for each closure of the contacts 40a. The decay of the stopping pulse voltage which is supplied by the capacitor 16 to the grid circuit of the oscillating valve is represented in Fig. 5 by the logarithmic curve 43.

At the time T_1 , the grid voltage has decayed to the value E_{ch} which is the value required to prevent oscillations from being initiated. At this time the voltage impressed on the output terminals of the polyphase rectifier 31 from the grid bias resistor becomes less than the voltage of the rectifier and consequently the rectifier impresses a negative hold-off voltage between ground and terminal 11. This hold-off voltage is sufficient to prevent further oscillation.

To restore the condition of oscillation, the valves 32, 33 and 34 are prevented from firing thereby removing the negative hold-off voltage which is supplied to the grid bias resistor 10. This is accomplished by releasing the push button switch 39 to interrupt the energizing circuit for the operating coil of the contactor 40. In response to deenergization the contactor 40 opens its normally open contacts 40a and 40b and closes its normally closed contacts 40c and 40d. During the time when the contacts 40b were closed, the capacitor 44 became charged from the voltage across the resistor 29 of the voltage divider. The polarity of the voltage of the capacitor 44 is plus at the ground terminal and negative at the grid terminal. Consequently, when the contacts 40d close, negative voltage is

impressed on the grids of the valves 32, 33 and 34, with the result that these valves cease conducting. As soon as the hold-off voltage disappears, oscillation is resumed in a normal manner.

Although in accordance with the provisions of the patent statutes this invention is described as embodied in concrete form and the principle thereof has been explained together with the best mode in which it is now contemplated applying that principle, it will be understood that the elements shown and described are merely illustrative and that the invention is not limited thereto since alterations and modifications will readily suggest themselves to persons skilled in the art without departing from the true spirit of this invention or from the scope of the annexed claims.

What we claim as new and desire to secure by Letters Patent of the United States, is:

1. In combination an electric valve oscillator comprising an electric valve having a cathode and a control grid and a bias resistor connected between said grid and cathode, means for terminating the oscillations of said oscillator comprising a circuit in parallel with said bias resistor including a capacitor and a second electric valve, means for charging said capacitor and means for firing said second valve to discharge said capacitor to supply to said grid a negative pulse voltage having a rate of decay substantially equal to the rate of decay of said oscillations, and means for supplying to said grid a negative hold-off voltage having a substantially smaller magnitude than said pulse voltage.

2. In combination an electric valve oscillator comprising an electric valve having a cathode and a control grid and a bias resistor connected between said grid and cathode, means for terminating the oscillations of said oscillator comprising a circuit in parallel with said bias resistor including a capacitor and a second electric valve, means for charging said capacitor and means for firing said second valve to discharge said capacitor to supply to said grid a negative pulse voltage having a rate of decay substantially equal to the rate of decay of said oscillations, means for supplying to said grid a negative hold-off voltage having a substantially smaller magnitude than said pulse voltage comprising a polyphase rectifier having its direct current terminals connected to said bias resistor, and means for supplying a polyphase alternating voltage to said rectifier smaller in magnitude than the portion of the bias voltage across said terminals whereby said rectifier is maintained inactive during oscillation.
